UNITED STATES PATENT OFFICE.

FRED. N. HACKETT, OF DETROIT, MICHIGAN.

GIG-SADDLE.

SPECIFICATION forming part of Letters Patent No. 461,384, dated October 13, 1891.

Application filed April 10, 1891. Serial No. 388,392. (No model.)

To all whom it may concern:

Be it known that I, FRED. N. HACKETT, of the city of Detroit, in the county of Wayne, in the State of Michigan, have invented a certain new and useful Improvement in Gig-Saddles; and I do declare the following to be a specification thereof, reference being had to the accompanying drawings.

Like letters indicate like parts.

Figure 1 is a view of a gig-saddle, partly in front elevation and partly in section, on the lines xx and zz of Figs. 2 and 3. Fig. 2 is a top plan of the under iron of said saddle with the burr in position. Fig. 3 is a top plan of a portion of one of the flaps of the saddle, showing the slot and burr therein and, by dotted lines, the under iron in position. Fig. 4 is a side elevation of the under iron and the burr in combination. Fig. 5 is a sectional view of the same on the line xx of Fig. 2. Fig. 6 is an end elevation of the under iron. Figs. 7 and 8 are respectively a top plan and a side elevation of the burr.

My invention relates to saddlery, and particularly to that portion of a harness known as the "gig-saddle."

It consists of an under iron having one or more elliptical slots lengthwise in the center and transverse ribs or stops on each side between said slots and the edges of the under iron, in combination with a burr and the other usual parts of a gig-saddle, as hereinafter particularly specified.

A represents the outer portions of a gig-saddle of usual construction, made preferably of leather. On each of the flaps an elongated or elliptical slot or opening a is made through the upper leather or covering, as fully shown in Fig. 3. The flaps are padded upon the under side, as seen at B in Fig. 1. One of these pads is illustrated in said figure in side elevation and the other in section in the line zz of Fig. 3. The pads are filled with hair or other suitable substance, as usual. The under irons are stiffening-pieces, and serve also to hold in position the burrs which support the terrets.

My improvement more especially refers to the under iron. It is marked C in the draw-

ings. It is made of metal and has a slightly- 50 concaved top and a slightly convex bottom, as seen in Fig. 6. Through the center, longitudinally, is one or more slots b , elongated or elliptical in shape, as shown in Fig. 2. There are short ribs c located transversely 55 upon the under surface, extending from the outer edge on each side to a line in continuation of the side lines of said slots b . These ribs serve as stops. Small holes or openings d are made near the edges of the iron. 60

D is a burr, having the tubular portion e internally screw-threaded and the flanges f extending therefrom in two opposite directions, as shown in Figs. 7 and 8. A terret E , having the usual ring g , seat h , and shank m , 65 which is screw-threaded at its end, is supported in the burr by the screw connection, as seen in elevation in Fig. 1 and in cross-section in Fig. 3.

A lining-piece F , preferably of leather, is 70 tacked at n through the holes d to the outer leather or covering of the flap, as seen in section in Fig. 1. This lining F protects the hair or padding from the movable parts and affords a space for said parts.

The parts are assembled as follows: When the under iron C has been properly placed and the lining F is tacked to the flap through the holes in the iron C , a burr D is inserted longitudinally, end foremost, through the slot 80 a of the flap and through a slot b of the under iron until the undersurface of the flanges f of said burr lies against the lining F . The burr D is then turned to the position indicated in Figs. 2 and 3, and the ribs c prevent it from turning too far. The flanges f , underlying the iron C when in this position, 85 prevent the burr from coming out, and, as they strike against one or more of the ribs c , are not permitted to turn too far. When the 90 terret E has been fastened by its shank m being screwed into the tubular portion e of the burr, the latter is tightly clamped by said screw connection and the forcible pressure of the seat h upon the exterior of the flap 95 thereby caused.

By this device a saddle is much more quickly trimmed than by the present meth-

ods, and a saving in time and expense is effected.

I claim as a novel and useful invention and desire to secure by Letters Patent—

5 In a gig-saddle, the combination of the flaps having the openings *a*, the under iron *C*, having the elongated slots *b* and transverse ribs *c*, the flanged and screw-threaded burr *D*, and

the terret *E*, having the seat *h* and screw-threaded shank *m*, all arranged and operating substantially as and for the purpose specified.

FRED. N. HACKETT.
